UNITED STATES PATENT OFFICE

FREDERICK C. WASHBURN, OF NEW BEDFORD, MASSACHUSETTS

WARP BEAM

Application filed March 13, 1928. Serial No. 261,392.

This invention relates to warp beams and has for its principal object the provision of a warp beam or roll of simple and durable construction which may be driven at high speed without damage to the beam or to the yarn wound thereon. Other objects are to provide a segmental wooden beam which may be readily assembled and conveniently turned down to proper diameter; to provide improved means for so connecting the beam cylinder to its heads as to insure rigidity of the assembled beam and prevent relative rotation between these elements; and to provide improved construction of the abutting surfaces of the roll and head, respectively, whereby the pinching or breaking of the yarn at said joint is prevented and whereby the bending stresses upon the beam shaft and relative rotation of beam head and barrel are resisted.

20 A recommended embodiment of the invention is shown for the purpose of illustration in the accompanying drawings, in which:

Fig. 1 is a broken longitudinal section of the improved warp beam;

25 Fig. 1^a is a detail similar to Fig. 1 showing a modification;

Fig. 2 is an end view of the same;

Fig. 3 is an enlarged transverse section taken on the line 3—3 of Fig. 1;

30 Fig. 4 is an enlarged transverse section through the warp roll, taken on the line 4—4 of Fig. 1;

Fig. 5 is a fragmentary longitudinal section through one end of the beam, taken on the line 5—5 of Fig. 4; and

35 Fig. 6 is a fragmentary developed section of the abutment joint between the cylinder and head, taken on the cylindrical surface 6—6 of Fig. 5.

40 The warp beam comprises in general a cylinder or barrel 7, preferably of built-up construction and consisting of interlocking longitudinal wooden staves, some of which are secured upon interior supports, a pair of beam heads 8 of wood or other suitable material and having a grooved peripheral metal belt seat 9, and a beam shaft 10 passing axially through the heads and stave supports and tensioned by nuts 11 on threaded ends of the shaft 10 adapted to clamp the heads tightly against

the barrel ends. As shown in Fig. 1, the nuts 11 may be formed as sleeves entering a central bore in and bearing for heads 9; in some cases, the nuts 11^a may be exterior to the heads, which are then bored to fit the shaft 10 (Fig. 1^a). A metal reinforcing plate or disc 12, preferably let into the outer faces of each respective beam head and extending outwardly to overlie the respective ends of the roll 7, is preferably provided to furnish a firm and even bearing surface for the nut and to assist in rigidly clamping the heads to the barrel ends.

45 The barrel 7 is preferably constructed by mounting four similar staves 13 upon the respective ends of a series of crossed supporting members 14 and 15, which may consist of stout wooden blocks rigidly secured face to face and at right angles to each other by gluing and by nails 16, or by other suitable fastening means. Bolts 17 and 18, having their heads received within counterbored openings in the staves and bearing upon metal washers 19 and 20, respectively, may be employed to fasten the staves upon the ends of the respective supporting blocks 14 and 15, these blocks having transverse openings 21 at the ends of the bolts to permit nuts 22 to be threaded thereon. The staves 13 preferably have longitudinal grooves in their beveled edges, adapted to receive complementary tenons of four other staves 23 which are driven endwise between the staves 13 to provide a compact and closely united segmental cylinder. The outside of the assembled cylinder may then be turned down to a smooth surface of the desired diameter and the counterbores in the staves may be plugged by bungs 24.

50 The number of the crossed supporting members used depends upon the length of the beam, one of the supports preferably being disposed near each end of the barrel in proximity to the beam head, in order that one block of each end member may form part of a clutch which is adapted rigidly to connect the head to the barrel so that relative rotation thereof is effectively restrained and whereby torsion strain upon the beam shaft and its tension nuts is relieved. The other cooperating element of the clutch preferably com-

prises a pair of metal flanges of angle plates 25 spaced in parallel relation, one on each side of the beam shaft, and secured to the inner face of each beam head, as by the bolts 26, 26 which pass through the head and the other flange of the angle plates 25 and may also serve to attach the reinforcing plate 12 to the outer face thereof, as best shown in Fig. 5. The plates 25 are so positioned that

10 their upstanding flanges constitute jaws to receive and mate with one of the blocks of the end roll supporting member, for example the block 15, Figs. 4 and 5. The supporting block being rigidly fixed to the barrel 7, the latter 15 is accordingly so connected by the clutch to the beam head that rotational movement between the parts is largely prevented, even though the beam and its yarn load be rotating at a high speed, and one or both of the heads 20 under braking restraint.

In order further to provide means to prevent such relative movement and to ensure against pinching or breaking of the yarn at said joint, the meeting surfaces of the 25 barrel end and beam head may be in annular grooves 27 and depressed below the surfaces 8^a of the heads and so formed as to present in any rotative sense complementary interengaging portions, preferably so arranged 30 that the end of each stave is received within the inner face 8^a of the head and interlocked with the head at spaced intervals, as indicated at 27, 27^a (Figs. 5 and 6). The abutting faces may accordingly 35 have interfitting radial ribs and grooves or other interlocking or frictionally engaging elements adapted to prevent or restrain relative rotational movement; but the provision of rounded, relatively shallow radial grooves 40 and contiguous cooperating ribs, which in developed section constitute complementary sinusoidal or other cam faces (Fig. 6) is recommended. Such a construction permits a slight relative turning movement without 45 damaging the interfitting portions and, in case such movement occurs, the result is not disadvantageous since it resolves into longitudinal movement and serves to increase the tension on shaft 10 and therefore support the 50 shaft further against flexing strains and holds the parts more rigidly together.

Locking means adapted to prevent turning of the tension nuts 11 are preferably provided, and may comprise metal locking rings 55 or washers 28 having one or more interior lugs 29 adapted to fit between the teeth 30 of the castellated hub of the nuts 11, when the nuts are sufficiently tightened by means of a wrench applied to their polygonal heads. 60 While the nuts 11 are being set up, the ring lugs may be received in annular grooves 31 of the nut hubs; and when the nut is to be locked, the rings may be secured by means of pins 32 Fig. 1, or 32^a Fig. 1^a, which are carried by 65 the reinforcing plates 12 and which extend

through appropriate apertures in the locking rings, cotter pins 33 being provided to prevent casual dislodgment of the rings. As shown in Fig. 1, these pins may be the projecting ends of bolts 32 in bores in the heads 8 having threaded ends screwed into tapped holes in plate 12, and extending outwardly through the bores in plate 28, which are not tapped.

A warp beam constructed as above described and herein claimed is simple and economical to manufacture, easy to assemble and to take apart in case repairs should become necessary, and particularly strong and durable in use without having excessive weight, 75 as well as useful to attain the several objects of this invention mentioned above; the particular details of construction may be varied within the definitions of the claims as desired without departing from the invention. 80

I claim:

1. A warp beam comprising a hollow wooden cylinder composed of a plurality of interlocking longitudinal staves and supporting members within the cylinder adapted 90 to be mounted upon a beam shaft, some of the staves being rigidly secured to the supporting members and the intermediate staves being sustained by the interlocking connection between them and the supported staves, beam 95 heads mounted on the ends of the cylinder, and clutch members carried by the beam heads and engaging respective supporting members to restrain relative rotation between the cylinder and its heads. 100

2. A warp beam comprising a hollow wooden cylinder composed of an even number of interlocking longitudinal staves, and supporting members within the cylinder adapted to be mounted upon a beam shaft, alternate staves being rigidly secured to the supporting members and the intermediate staves being sustained by the interlocking connection between them and the supported staves. 110

3. A warp beam comprising a hollow wooden cylinder composed of an even number of longitudinal staves, supporting members within the cylinder and adapted to be mounted upon a beam shaft, alternate staves 11 being rigidly secured upon said supporting members, and longitudinal tongue and groove connections between adjacent staves, whereby the staves intermediate the secured staves may be driven endwise between and be sustained by said secured staves. 120

4. A warp beam comprising a hollow wooden cylinder composed of eight longitudinal staves, supports within the cylinder and adapted to be mounted upon a beam 12 shaft, each support consisting of a pair of crossed wooden blocks, fastening means rigidly securing four alternate staves upon the ends of the respective blocks, and longitudinal tongue and groove connections for 13

uniting adjacent staves, whereby the other four staves may be driven endwise between and may be supported by said secured staves.

5. A warp beam comprising a hollow wooden cylinder composed of a series of longitudinal staves, supports within the cylinder secured to some at least of said staves, beam heads on the ends of said cylinder, one of said supports being positioned near each beam head and the supports and beam heads being adapted for mounting upon a beam shaft, and a pair of flanges removably secured in spaced parallel relation upon the inner face of each beam head, one on each side of the shaft, said flanges providing clutch jaws receiving a portion of one of the end supports, whereby relative rotation between the beam heads and the cylinder is restrained.

6. A warp beam comprising a hollow cylinder, supports within the cylinder adapted to be mounted upon a beam shaft, each support consisting of a pair of crossed members and one of the supports being positioned near each end of the cylinder, beam heads on the ends of the cylinder mounted on the shaft, and a pair of flanges secured in spaced parallel relation upon the inner face of each beam head, one on each side of the shaft, said flanges providing clutch jaws receiving one member of an end support, whereby relative rotation between the beam heads and the cylinder is restrained.

7. A warp beam comprising a hollow cylinder, supports within the cylinder adapted to be mounted upon a beam shaft, each support consisting of a pair of crossed members and one of the supports being positioned near each end of the cylinder, beam heads on the ends of the cylinder mounted on the shaft, the ends of the cylinder abutting the inner face of the respective beam heads and the abutting surfaces having interengaging portions, and a pair of flanges secured in spaced parallel relation upon the inner face of each beam head, one on each side of the shaft, said flanges providing clutch jaws receiving one member of an end support, whereby relative rotation between the beam head and the cylinder is restrained.

8. A warp beam comprising a hollow wooden cylinder composed of a plurality of interlocking staves, an axial beam shaft, stave supports mounted on said shaft within the cylinder, beam heads mounted on the shaft and abutting the ends of the cylinder, a pair of flanges on the inner face of each beam head, and a reinforcing plate on the outer face of each head, means passing through each flange, head and plate for securing the flanges and plates to the head, each pair of flanges having clutch jaws engaging one of the stave supports, nuts on the beam shaft and bearing against the respective reinforcing plates to clamp the heads on the cylinder, locking rings adapted to engage with said nuts, and pins carried by the reinforcing plates and received

by the respective locking rings to prevent turning of the rings.

9. A warp beam comprising a hollow wooden cylinder composed of an even number of interlocking longitudinal staves, a beam shaft extending axially through the cylinder, alternate staves being rigidly secured to the supporting members and the intermediate staves being sustained by the interlocking connections between them and the secured staves, beam heads mounted on the shaft and abutting the ends of the cylinder, the inner face of each beam head being mortised to receive the cylinder ends, one of the supporting members being positioned near each beam head, a pair of metal flanges secured in spaced parallel relation upon the inner face of each beam head, one on each side of the shaft, said flanges providing clutch jaws engaging one of the end supporting members, and means for clamping the beam heads on the cylinder.

10. A warp beam comprising a hollow cylinder composed of an even number of longitudinal wooden staves, a beam shaft extending axially through the cylinder, stave supports mounted on the shaft within the cylinder and consisting of crossed wooden blocks, alternate staves being rigidly secured upon the ends of the respective blocks, longitudinal tongue and groove connections between adjacent staves whereby the staves intermediate the secured staves may be driven endwise between and be sustained by said secured staves, beam heads mounted on the shaft and abutting the ends of the cylinder, the inner face of each beam head being mortised to receive the cylinder ends, one of the crossed supports being positioned near each beam head, clutch means carried by each beam head and receiving and mating with the sides of one block of each end support, and means on the shaft for clamping the beam heads on the cylinder.

Signed by me at New Bedford, Massachusetts this 9th day of March, 1928.
